(57) **CLAIM**

The ornamental design for an ovulation scope, as shown.

DESCRIPTION

Ovulation scopes are used to assess the state of fertility of women by examining dried saliva for the presence or absence of crystallization in dried female saliva.

FIG. 1 is a front perspective view of an ovulation scope showing my new design; and,

FIG. 2 is a rear perspective view thereof.

1 Claim, 1 Drawing Sheet

FIG. 1

FIG. 2
